ABSTRACT OF THE DISCLOSURE

Potassium azide is produced by precipitation from a solution of dissolved sodium azide and potassium carbonate. By conducting precipitations of potassium azide and by-product sodium carbonate at two different temperatures, a cyclic process may be achieved.

SUMMARY OF THE INVENTION

This invention deals with the production of potassium azide. It more particularly relates to the production of potassium azide from sodium azide and potassium carbonate by double replacement. An additional feature of the invention allows potassium azide to be produced in a cyclic process.

BRIEF DESCRIPTION OF THE DRAWINGS

FIG. 1 is a Jänecke plan projection of a portion of the $\text{NaN}_3\text{-K}_2\text{CO}_3$ reciprocal salt pair system at 25° C.

FIG. 2 is a superimposition of the Jänecke plan projections of portions of the $\text{NaN}_3\text{-K}_2\text{CO}_3$ reciprocal salt pair system for the 25° C. and 80° C. isotherms.

FIG. 3 is a Jänecke projection of a portion of the $\text{NaN}_3\text{-K}_2\text{CO}_3$ reciprocal salt pair system with water at 25° C.

FIG. 4 is a Jänecke projection of a portion of the $\text{NaN}_3\text{-K}_2\text{CO}_3$ reciprocal salt pair system with water at 80° C.

FIG. 5 is the water elevation of a portion of the Jänecke projection for the $\text{NaN}_3\text{-K}_2\text{CO}_3$ reciprocal salt pair system at 25° C.

FIG. 6 is similar to FIG. 2, showing a process according to this invention.

FIG. 6A is a superimposition of the water elevations of portions of the Jänecke projections for the $\text{NaN}_3\text{-K}_2\text{CO}_3$ reciprocal salt pair system at 25° C. and 80° C. further showing the process of FIG. 6.

FIG. 6B is an enlargement of the central portion of FIG. 6A.

FIG. 7 is similar to FIG. 6, showing a modified process according to this invention.

FIG. 7A is similar to FIG. 6A, further showing the modified process of FIG. 7.

FIG. 8 is similar to FIG. 6, showing another modified process according to this invention.

FIG. 8A is similar to FIG. 6A, further showing the modified process of FIG. 8.

FIG. 9 is a flowsheet of a cyclic process according to this invention.

DETAILED DESCRIPTION

Potassium azide may be produced by precipitating the same from an aqueous solution containing significant quantities of sodium ions, potassium ions, azide ions and car-

2

bonate ions. A quantity is significant in this respect when each of the four enumerated ions is present in solution at a concentration of at least 1 percent by weight of the total anhydrous salts comprising the solution. Thus, each of these ions is present in solution in more than mere trace or contaminating amounts. Such a solution may be formed from sodium azide, potassium carbonate and water. Potassium azide is then precipitated from the solution. Whether the enumerated ions are simple or complex or whether they are truly ionic in the classical sense, is of secondary consideration. The important characteristic of these substances is that they are able to undergo rearrangement from the parent feed materials to form potassium azide and sodium carbonate.

When referring to reciprocal salt pair systems, it is convenient to represent the system by means of the Jänecke projection. General reference in this regard may be made to Purdon and Slater, *Aqueous Solution and the Phase Diagram*, Edward Arnold & Co., London (1946).

Referring now to FIG. 1, there is shown a Jänecke projection of a portion of the aqueous system

at 25° C. where each corner of the square represents a pure salt. Each salt of a salt pair is positioned at the end of a diagonal opposite from the other. Each corner not only represents a pure salt, but implies a definite quantity of that salt, usually, but not necessarily, one chemical equivalent. Chemical equivalents are used rather than moles or grams since the above equation indicates that one molecule of sodium azide or potassium azide is equivalent to one-half molecule of sodium carbonate or potassium carbonate.

If the corners are taken as representing one equivalent of the pure substance, any point within the diagram represents one equivalent of mixed salts with the amount of water unspecified. Since one equivalent of any salt will yield two equivalents of ions, the sum of the cations equals one equivalent and the sum of the anions also equals one equivalent.

Each side of the square is a straight line connecting compounds having a common ion. The top horizontal edge of FIG. 1, for example, connects the corners representing potassium carbonate and potassium azide. The common ion in this case is the potassium ion. For any point on the diagram, the amount of potassium ion present in solution may be found by passing a vertical line through the point and applying the well-known principle of the lever rule, where the top horizontal edge of the square indicates that all the cations are potassium ions. According to the lever rule, the fraction of cations which are potassium ions is represented by the proportion ps/rs and the fraction of cations which are sodium ions is given by pr/rs . The rule derives its name from an analogy with the lever-arm principle of mechanics. According to this analogy, if all of the potassium ions were placed at point r on beam rs , all of the sodium ions placed at point s and the fulcrum positioned at point p , the hypothetical beam rs will be in balance if the amounts of potassium ions and sodium ions placed at points r and s respectively are inversely proportional to their distances from the fulcrum. Thus, for point p on the diagram, the concentration of potassium ions is represented by the ratio ps/rs multiplied by the quantity of salt represented by a corner. If the quantity of salt represented by each corner is one chemical equivalent, the potassium concentration is $(ps)/(1.0)/rs = 0.7$ equivalent.

Similarly, the concentration of sodium ion is $(pr)(1.0)/rs = 3.0$ equivalent. The concentration of anions may be found in an analogous manner by measuring the relative position of point p from the two vertical edges of the square. Moreover, since the basis is one equivalent of salts, scales may be positioned at the edge of the square indicating equivalent fractions. While the level rule has been described with respect to ions, it is equally applicable to compounds, salt mixtures and solutions which appear on the projection.

While a point on the diagram may be represented in terms of its ions, it is often convenient to express its position in terms of salts. Since any mixture of four possible salts can be expressed in terms of three salts, any point in the square may be regarded as being in an isosceles right triangle, or half a square. Point p is in the triangle

Only two figures are required to fix the position of the point, and it is most convenient to take the figures for the salts at opposite ends of a diagonal, which in this case are KN_3 and Na_2CO_3 . The amount of salt represented by the salt at the right angle of the triangle is equal to the total amount of salt represented by the system less the sum of the amounts of salt whose identities are represented by the salts at ends of the diagonal. In FIG. 1 the composition of point p expressed in terms of three salts is $(r \cdot \text{K}_2\text{CO}_3)(1.0)/rs = 0.6$ equivalent KN_3 , $(pr)(1.0)/rs = 0.3$ equivalent Na_2CO_3 and

$$1.0 - (0.6 + 0.3) = 0.1$$

equivalent K_2CO_3 . It will be seen that the amount of the third component, K_2CO_3 , is equal to $(pw)(1.0)/(rs)$ where pw is the distance from point p to the diagonal which is measured parallel to a side of the square. Even though the composition of point p may be expressed in terms of percentages of KN_3 , Na_2CO_3 and K_2CO_3 , it is, of course, understood that physically these salts need not be present as the salts per se, but may actually be present in some other form such as ions. For this reason, the composition of point p may be equally as well expressed in terms of the salts K_2CO_3 , Na_3N and KN_3 since point p is also located within the triangle $\text{K}_2\text{CO}_3 \cdot \text{Na}_3\text{N} \cdot \text{KN}_3$. The principles are analogous to those just described.

In the absence of a water elevation or solid model, both of which will be more fully described hereafter, it is assumed that the water content of a point of the Jänecke projection is such that the solution is saturated. Curves AE, BE, EF, CF and DF are then placed upon the square, which divide it into four areas known as fields. Any point within a field represents the composition of a solution which is saturated with respect to one salt. The identity of the salt is indicated by the corner, but the degree of hydration, if any, is undefined. Thus, the solution point p is saturated with respect to potassium azide.

A point on any of the curves AE, BE, EF, CF or DF, represents a solution saturated with respect to two salts. These two salts are indicated on an anhydrous basis by the two corners of the adjacent fields. Point t , for example, is saturated with respect to sodium carbonate and potassium azide. The points E and F are quaternary invariant points which represent solutions saturated with respect to three salts represented by the corners of the adjacent fields. Thus, the point F is saturated with respect to sodium carbonate, sodium azide and potassium azide.

When water is isothermally evaporated from a solution saturated with respect to one simple salt or one hydrated simple salt, that salt, which is represented by the corner of the field, precipitates and the composition of the solution moves away from the corner of the field along a straight line passing through the corner of the field and the point representing the initial solution composition. As water is isothermally evaporated from the saturated solu-

tion of point p , potassium azide precipitates and the solution composition moves to point u . The fraction of the total salts precipitated as potassium azide is $up/u \cdot \text{KN}_3$, in accordance with the lever rule. Additional water may be removed with the concomitant precipitation of potassium azide until the solution composition reaches point t . The lever rule may again be applied to determine the fraction of total salts precipitating as potassium azide. Any further removal of water will result in the precipitation of both potassium azide and sodium carbonate while the solution composition moves along the curve EF towards point E. Upon reaching point E, the solution composition will remain constant as potassium azide, sodium carbonate and potassium carbonate are precipitated from solution. Continued isothermal evaporation of water will result in the drying of the solution. During the entire isothermal evaporation procedure, the over-all composition of the complex, irrespective of the number of phases present, will be represented by point p . This point will continue to represent the over-all composition until one or more salts are added to or removed from the system.

FIG. 2 shows the Jänecke projection of FIG. 1 having a similar projection for the 80° C . isotherm super-imposed upon it. With the change in temperature from 25° C . to 80° C . A has moved to A' , B to B' , C to C' , D to D' , E to E' and F to F' . Precipitations may be represented in a manner analogous to the procedure using the 25° C . isotherm.

FIG. 3 represents the basic Jänecke projection of FIG. 30 1, having a scale representing moles of water per equivalent of anhydrous salts projected vertically from the base plane which represents the salts. The resulting diagram may be thought of as representing a three-dimensional solid, but the plan has not been shown foreshortened in the interests of ease of drawing and ease of comparison with the plan projection of FIG. 1. Pure water is represented by a point infinitely distant from the plan. Above the plan are shown the surfaces representing the water content for a saturated solution. Any point on the saturation surface represents a saturated solution and any point above a saturation surface represents an unsaturated solution. A point between the saturation surface and the plan represents the over-all composition of a system having a solid phase and a saturated solution. A straight line connects the point representing the solid phase composition, the point representing the overall composition (the complex) and the point representing the saturated solution. The lever rule may be applied to determine the relative amounts of solid phase and saturated solution. Any point on the plan represents anhydrous salts.

Upon the isothermal evaporation of water from an unsaturated starting solution, p_2 , the solution point, will descend vertically until it reaches the saturation surface at point p_1 . Further isothermal evaporation of water will result in the precipitation of potassium azide and the movement of the solution point along the curve Nt_1 on the saturation surface from p_1 towards t_1 . Upon reaching point t_1 , the continued evaporation of water causes the point representing the solution to move along curve E_1, F_1 , to E with the precipitation of potassium azide and sodium carbonate. As additional water is removed, the solution composition remains at E_1 and the three salts of the adjacent fields precipitate. This precipitation continues until the solution dries. Similar diagrams may, of course, be constructed for other isotherms. Representative of these is FIG. 4, constructed for the 80° C . isotherm.

Instead of using a solid model or a diagram representing the same, it is often more convenient to use an elevation projection illustrating the water content. FIG. 5 is the water elevation of a portion of the $\text{Na}_3\text{N} \cdot \text{K}_2\text{CO}_3$ reciprocal salt pair system at 25° C . looking in the direction shown by the arrow in FIG. 3. Again, isothermally evaporating water from unsaturated solution p_2 , the se-

quence of events is the same. The point representing the solution composition moves from p_2 to p_1 , from p_1 to t_1 with the precipitation of potassium azide, from t_1 to E_1 with the precipitation of potassium azide and sodium carbonate, from E_1 to E with the precipitation of potassium azide, sodium carbonate and potassium carbonate. In order to exemplify more clearly the basic principles involved, FIGS. 3, 4 and 5 do not show the formation of hydrates.

FIGS. 6 and 6A show the plan and water elevation, respectively, of portions of the 25° C. and 80° C. isotherms and may be used to illustrate the phenomenon of cooling. FIG. 6B is an enlargement of the central portion of FIG. 6A and more clearly shows the relationship of several of the points in this region of FIG. 6A.

The effect of cooling solution a_1 , which is saturated with respect to potassium azide and sodium carbonate, may best be demonstrated by considering a hypothetical process where water is added at 80° C. to saturated solution a_1 until the solution point is at some point a_2 above the curve b_1N . Upon cooling to 25° C., the solution point remains at a_2 since no material precipitates or is removed from the system. When water is isothermally removed at 25° C., the solution point descends vertically until it reaches the curve b_1N at a_3 . The solution is now saturated with respect to potassium azide. With the continued removal of water, potassium azide precipitates and the solution point moves from a_3 towards d_1 . The over-all composition point continues to descend vertically since only water is being removed from the system. The relationship of the solution point, the over-all composition point and the corner representing potassium azide is such that a straight line connects all three points. When the over-all composition reaches point a_1 , the solution point reaches d_1 . At this stage of the hypothetical process, the same amount of water that was added to solution a_1 has been removed, returning the over-all composition to point a_1 . In the interim, however, the system was cooled and potassium azide precipitated. While it is permissible to add and then remove the water in an actual process, it is more convenient to simply cool solution a_1 from 80° C. to 25° C. with the precipitation of potassium azide. The result is the same: over-all composition a_1 contains precipitated potassium azide and saturated solution d_1 .

FIGS. 6 and 6A may also be used to illustrate a cyclic process for the production of potassium azide from sodium azide and potassium carbonate. Sodium azide and potassium carbonate are dissolved in the proper proportions to form a saturated solution at 80° C. represented by the point e_1 . Water is then isothermally evaporated, moving the solution point from e_1 to a_1 , with the deposition of sodium carbonate monohydrate. The precipitate is removed from the system, leaving solution a_1 . Centrifugation or filtration may be used for this purpose. Solution a_1 is then cooled from 80° C. to 25° C., resulting in solution d_1 and precipitated potassium azide. Water is isothermally evaporated at 25° C. to deposit more potassium azide until the solution point reaches b_1 . The solid potassium azide is next removed from the solution. Centrifugation or filtration is useful for this purpose. Solution b_1 is then heated to 80° C. A mixture of sodium azide and potassium carbonate, represented by point o is added to solution b_1 to form complex c_3 at 80° C. Water is added to complex c_3 which is saturated with respect to sodium carbonate monohydrate to form saturated solution c_1 . A slight excess of water may be added to form solution c_2 to insure dissolution of all of the salt. Water is isothermally evaporated at 80° C. to deposit sodium carbonate monohydrate until the solution composition reaches point a_1 . The sodium carbonate monohydrate is then removed from the system. Solution a_1 may again be cooled to 25° C. and the cycle repeated as often as desired.

Since the Jänecke projection represents equilibrium conditions, it does not indicate the rates of transformation during various stages of the process. When, for example, mixture o is added to solution b_1 at 80° C. to form com-

plex c_3 , time must be allowed for a portion of the solid phase to dissolve and for the remaining portion to be converted to sodium carbonate monohydrate. If left long enough to assure equilibrium conditions, complex c_3 would provide solution a_1 and solid sodium carbonate monohydrate. The time lag may be substantially reduced by dissolving mixture o in the water necessary to form saturated solution o_1 . This solution is then added to solution b_1 to form unsaturated solution c_2 . Water is isothermally removed from solution c_2 to form saturated solution c_1 . The precipitation of sodium carbonate monohydrate may then be accomplished with the further evaporation of water as heretofore described.

In order to insure the complete dissolution of the proper amount of mixture o , it is preferable to use a slight excess of water to form unsaturated solution o_2 . When this solution is mixed with solution b_1 , the unsaturated solution c_4 is formed. The isothermal evaporation of water at 80° C. will cause the solution point to move from c_4 to c_1 , from whence the precipitation may begin.

It is preferred that the temperature of feed solution o_1 or o_2 and the temperature of solution b_1 be about 80° C. when the solutions are mixed. This is not strictly necessary, however. The temperature of the feed solution may be greater or lesser than that of solution b_1 . Of course, if the temperature of a solution is cooled below the point at which it becomes saturated, salt will ordinarily precipitate. This is not the preferred mode of operation since long periods of time are often required to bring the mixture to equilibrium. If solutions of divergent temperatures are to be mixed, it is preferred that the temperatures and specific heats be such that the resultant temperature of the mixture be at the desired temperature for the evaporation of water, in this instance, about 80° C. Otherwise, heating or cooling of the mixture is required.

FIGS. 7 and 7A illustrate one modification of the basic process which may be used to advantage. When solution d_1 is formed by the cooling of solution a_1 , additional potassium azide may be precipitated by isothermally evaporating water to move the solution point from d_1 to b_1 as heretofore described. The isothermal removal of water at 25° C. is, of course, a slow process which may be accelerated by the application of a vacuum. This requires the expense of a vacuum system. Moreover, the additional amount of potassium azide precipitated by this step is moderate. It may be more advantageous to forego the immediate recovery of this amount of potassium azide. Once the precipitated potassium azide has been removed from solution d_1 , the solution may be heated to 80° C. and mixture o added to form complex f_3 . Water is then added to form saturated solution f_1 , or more preferably, unsaturated solution f_2 . Alternatively, solution o_1 , comprising salt mixture o and water, may be added to form solution f_2 . In order to assure complete dissolution of salt mixture o and the purity of the sodium carbonate monohydrate to be precipitated, it is preferable to add unsaturated solution f_4 . Water may then be isothermally removed at 80° C. to bring the solution point to f_1 . Continued isothermal evaporation of water moves the solution point to a_1 with the precipitation of sodium carbonate monohydrate. The precipitate may then be separated and solution a_1 cooled to precipitate potassium azide. Additional cycles may be performed as desired.

Obviously, this modification may be practiced only in part by isothermally removing only a portion of the water required to move the solution point from d_1 to point b_1 before adding mixture o or a solution thereof.

Another modification, which is the preferred mode of operating the system, is shown in FIGS. 8 and 8A. Here salts are precipitated only until the solution point approaches the lines of saturation with respect to two salts rather than touches them. This insures the purity of the salt by reducing the possibility for a precipitation of both salts due to short term fluctuations in the sur-

rounding conditions. Thus, solution g_2 , which approaches but does not coincide with point a_1 , may be cooled to form solid potassium azide and saturated solution k_1 which lies on curve m_1N . Water is next isothermally removed to reach point h_1 which approaches but does not coincide with point m_1 . If desired, water may be removed from solution g_2 as it is cooled, in which case the solution point reaches point h_1 without passing through point k_1 . Care must be exercised, however, to adjust the relative rates of evaporation and cooling so as to avoid the precipitation of two salts unless salt purity is of little consequence.

Upon reaching point h_1 , the precipitated potassium azide is then removed from the system. Solution h_1 is next heated to 80° C. Mixture o is then added to form complex j_3 . Water is added to form saturated solution j_1 or if water is in excess, unsaturated solution j_2 . Again, it is preferred to add a solution of mixture o rather than adding the solid salts. Saturated solution o_1 may be added to solution h_1 to form unsaturated solution j_2 . In order to assure that the salt mixture o is in solution, it is preferred to add unsaturated solution o_2 to solution h_1 to give unsaturated solution j_4 . Water is then isothermally evaporated at 80° C. from solution j_2 or solution j_4 , as the case may be, to produce saturated solution j_1 . Further isothermal evaporation precipitates sodium carbonate monohydrate while moving the solution point to point g_2 . The cycle may be repeated as often as desired.

It will be apparent that the cyclic process as a whole or any of its individual steps may be operated either continuously or intermittently. FIG. 9 illustrates a continuous process which may be used in accordance with this invention. A solution containing significant quantities of potassium ions, sodium ions, azide ions and carbonate ions is introduced into cooling crystallizer 1 through line 2. Mother liquor and the feed solution are circulated through line 4, and heat exchanger 6 by pump 8. Coolant is circulated through the heat exchanger to cool the circulating mother liquor and feed solution to about 25° C. The mother liquor, supersaturated with respect to potassium azide, is introduced to a bed of potassium azide crystals through line 9, vapor head 10 and leg 11. A vacuum may be applied to the vapor head if vapor is to be removed. Magma is withdrawn from the crystallizer through line 12 by pump 14. The magma is introduced to a centrifuge 16 where mother liquor is removed through line 18 and the crystals are removed through line 20. The crystals may be washed if desired, but this is not ordinarily necessary where the potassium azide is to be used for agricultural purposes. The crystals are then dried in dryer 22 while vapors are removed through line 24. Mother liquor is introduced to heat exchanger 26 where it is heated to about 80° C. The warm mother liquor then proceeds to mix tank 28 where it is combined with an aqueous solution of sodium azide and potassium carbonate which is introduced to mix tank 28 through line 30. The solution is withdrawn from mix tank 28, fed through line 32 and combined with the circulating mother liquor in evaporator-crystallizer 34. Circulation is provided by the pump 36. The circulating liquid is heated in heat exchanger 38 so the vapor will flash off in vapor head 40. A vacuum may be applied to the vapor head or not, as desired. The solution, supersaturated with respect to sodium carbonate monohydrate is passed through leg 42 and introduced into a bed of sodium carbonate monohydrate crystals where sodium carbonate monohydrate precipitates. Magma is withdrawn from evaporator-crystallizer 34 through line 44 by pump 46 and introduced to centrifuge 48. Mother liquor is removed from centrifuge 48 through line 2 and returned to cooling crystallizer 1. The azide remaining with the crystals is removed by wash water introduced through line 50. Azide-containing wash water is removed through line 52. This wash water may be sent to azide

destruction and disposal through line 53, but it is preferably forwarded to evaporator 54 through line 56. Sodium carbonate crystals are removed from centrifuge 48 through line 57 and sent to dryer 59 where water vapor is removed through line 61. The wash water fed to evaporator 54 is mixed with circulating liquor circulated through heat exchanger 58 by pump 60.

Vapor is flashed from the superheated liquid in evaporator 54. Concentrated solution containing azide and carbonate ions is then fed through line 64 to dissolver 66 where it is mixed with sodium azide and potassium carbonate. These solids are dissolved preferably by agitation while the solvent is circulated through heat exchanger 68 by pump 70. Solution at 80° C. is removed from the dissolver 66 and introduced to mix tank 28 through line 30. The evaporator may be eliminated, if desired, provided that the amount of water used to wash the sodium carbonate crystals does not exceed the water removed from other regions of the system. Should the system require make-up water, it may conveniently be added to dissolver 66.

By properly regulating the concentrations of the solutions in accordance with Jänecke's projection of the NaN_3 - K_2CO_3 reciprocal salt pair system, and by regulating the water balance of the system, a continuous process for the production of potassium azide is provided. This process also allows the byproduct sodium carbonate to be used for many purposes without further purification. Of course, the sodium carbonate leaving the dryer 59 may be anhydrous or in the form of the monohydrate, depending upon the amount of water being removed by the dryer. Ordinarily, only trace amounts of azide remain in this material.

The feed mixture O has been discussed with reference to the anhydrous salts, but it is often convenient to add mixtures containing hydrated salts such as potassium carbonate sesquihydrate or potassium carbonate dihydrate. The point representing the particular hydrate containing salt mixture which is used may be plotted on the Jänecke projection according to the principles heretofore described. Further lever rule calculations are then based upon this point.

Mixture O may be prepared indirectly rather than by the direct mixing of sodium azide and potassium carbonate. Thus, sodium azide and potassium hydroxide may be heated to form a melt into which carbon dioxide is introduced. The carbonated melt may then be cooled and introduced to the metathesis system with or without water in the form of anhydrous salt, hydrate or solution.

Carbonation may also be accomplished in aqueous solution. Thus, sodium azide and potassium hydroxide are dissolved in water and carbon dioxide is introduced to the solution. The salts of the carbonated solution are then introduced to the metathesis system in any of the forms described above. Alternatively, sodium azide and potassium hydroxide may be added to the metathesis system and carbonated in situ.

When concentrated wash water is added to the system, the following procedure can be used to determine the location of the point representing the salt mixture added to the system. If the point representing the concentrated wash water is plotted on the diagram, a straight line connecting this point with the point representing the feed salt mixture will pass through the point representing the composition of a mixture of the two. The precise location of the point on the line may be found by applying the lever rule. When this point is ascertained, it may be used in conjunction with the point representing the mother liquor from the potassium azide precipitation to find the composition of the resulting mixture by application of the lever rule.

While the system has been described on the basis of only four ions, it is, of course, possible to add additional ions or compounds to the solution. The effect of these additional ions or compounds upon the system depends upon their identity and concentration. Since these effects

cannot ordinarily be predicted with certainty, empirical methods are used in their determination. Foreign ions or compounds will occasionally cause the precipitation of double salts. This may be permitted where it is not necessary to obtain a product pure with respect to one salt.

The invention has been shown using particular points on the Jänecke projection, but it will be understood that the points used may be varied upon the diagram. This will change the lengths of the lever arms for the various calculations involving the lever rule.

The basic principles of the present invention have been incorporated by way of example in the following specific embodiments. In these examples, the location of the pertinent

equivalents (98.39 grams) of salts in solution as solution c_1 . Still at $80^\circ C$, 2.96 moles (53.34 grams) of water are isothermally removed precipitating 0.480 equivalent (25.44 grams) of sodium carbonate as the monohydrate. Since 0.24 mole (4.32 grams) of water is precipitated as water of hydration, 29.76 grams of sodium carbonate monohydrate is precipitated. This sodium carbonate monohydrate is then removed, leaving 1.000 equivalent (72.95 grams) of salts as solution a_1 . The separated sodium carbonate monohydrate is washed and dried. The separated potassium azide is dried. The cycle is summarized in Table II. Mother liquor left entrained with the crystals is deemed to be negligible.

TABLE II

EXAMPLE I

A cyclic process for producing potassium azide from sodium azide and potassium carbonate is performed which may be described with reference to FIGS. 6, 6A and 6B.

Using point a_1 as the starting point for the cycle and allowing point a_1 to represent 1.000 equivalent (72.95 grams) of salts, the solution is cooled from $80^\circ C$. to $25^\circ C$. while 0.326 equivalent (26.45 grams) of KN₃ precipitate, leaving 0.674 equivalent (46.50 grams) of salts as solution d_1 . Water in the amount of 1.37 moles (24.69 grams) is isothermally evaporated at $25^\circ C$. thereby precipitating an additional 0.154 equivalent (12.49 grams) of KN₃ and leaving 0.520 equivalent (34.01 grams) of salts as solution b_1 . Precipitated potassium azide in the amount of 0.480 equivalent (38.94 grams) is removed from the system. Solution b_1 is then heated to $80^\circ C$. Next, 0.960 equivalent (64.38 grams) of a salt mixture represented by point O which comprises 0.480 equivalent (33.17 grams) of potassium carbonate, 0.480 equivalent (31.21 grams) of sodium azide and 5.13 moles (92.44 grams) of water is added, at $80^\circ C$., to solution b_1 . At this point there are 1.480 equivalents (98.39 grams) of salts in solution as solution c_1 . Still at $80^\circ C$., 0.56 mole (10.09 grams) of water are isothermally removed, resulting in solution c_1 . Upon removing an additional 2.96 moles (53.34 grams) of water at $80^\circ C$., 0.480 equivalent (25.44 grams) of sodium carbonate and 0.24 mole (4.32 grams) of water of hydration precipitate as sodium carbonate monohydrate. This sodium carbonate monohydrate is then removed, leaving 1.000 equivalent (72.95 grams) of salts as solution a_1 . The separated sodium carbonate monohydrate is washed and dried. The separated potassium azide is dried. The cycle is summarized in Table III. Mother liquor left entrained with crystals is deemed to be negligible.

EXAMPLE II

A cyclic process for producing potassium azide from sodium azide and potassium carbonate is performed which may be described with references to FIGS. 6, 6A and 6B.

Using point a_1 as the starting point for the cycle and allowing point a_1 to represent 1.000 equivalent (72.95 grams) of salts, the solution is cooled from $80^\circ C$. to $25^\circ C$., while 0.326 equivalent (26.45 grams) of KN₃ precipitate, leaving 0.674 equivalent (46.50 grams) of salts as solution d_1 . Water in the amount of 1.37 moles (24.69 grams) is isothermally evaporated at $25^\circ C$., thereby precipitating an additional 0.154 equivalent (12.49 grams) of KN₃ and leaving 0.520 equivalent (34.01 grams) of salts as solution b_1 . Precipitated potassium azide in the amount of 0.480 equivalent (38.94 grams) is removed from the system. Solution b_1 is then heated to $80^\circ C$. Next, a solution represented by point o_2 which comprises 0.480 equivalent (33.17 grams) of potassium carbonate, 0.480 equivalent (31.21 grams) of sodium azide and 5.13 moles (92.44 grams) of water is added, at $80^\circ C$., to solution b_1 . At this point there are 1.480 equivalents (98.39 grams) of salts in solution as solution c_1 . Still at $80^\circ C$., 0.56 mole (10.09 grams) of water are isothermally removed, resulting in solution c_1 . Upon removing an additional 2.96 moles (53.34 grams) of water at $80^\circ C$., 0.480 equivalent (25.44 grams) of sodium carbonate and 0.24 mole (4.32 grams) of water of hydration precipitate as sodium carbonate monohydrate. This sodium carbonate monohydrate is then removed, leaving 1.000 equivalent (72.95 grams) of salts as solution a_1 . The separated sodium carbonate monohydrate is washed and dried. The separated potassium azide is dried. The cycle is summarized in Table III. Mother liquor left entrained with crystals is deemed to be negligible.

While the invention has been described with reference to the 25° C. and 80° C. isotherms, other isotherms may be used as desired. The maximum useful isotherm is the boiling point of the system under the environmental pressure involved while the minimum useful isotherm is the point at which the entire system freezes.

Water is the preferred solvent for the system. However, any material which is a solvent for potassium azide, sodium azide, potassium carbonate and sodium carbonate may be used provided potassium azide may be precipitated from solutions of these salts. The Jänecke projection of the NaN₃-K₂CO₃ reciprocal salt pair system may be constructed using a solvent other than water. Inspection of the projection and application of the principles applied in the aqueous system will indicate whether such a solvent is suitable for use in a cyclic or noncyclic process. Mixtures of solvents may also be used if desired.

It is to be understood that the terms potassium azide, sodium azide, potassium carbonate and sodium carbonate as used throughout the specification and claims are intended to include anhydrous salts, hydrates, simple salts and double salts unless otherwise qualified.

What is claimed is:

1. A method for producing potassium azide comprising:
  - (a) cooling a first aqueous solution containing at least one percent by weight of the total anhydrous salts present therein each of the following ions, sodium ions, azide ions, and carbonate ions, to precipitate potassium azide and to form a first mother liquor;
  - (b) separating said precipitated potassium azide from said first mother liquor;
  - (c) increasing the temperature of said first mother liquor to a second temperature which is higher than said first temperature;
  - (d) forming a second aqueous solution from sodium azide, potassium carbonate, water and said first mother liquor;
  - (e) removing water from said second aqueous solution to precipitate sodium carbonate from said second aqueous solution to form a second mother liquor; and
  - (f) separating said precipitated sodium carbonate from said second mother liquor.
2. The method of claim 1 wherein said first temperature is about 25° C.
3. The method of claim 1 wherein said second temperature is about 80° C.
4. The method of claim 1 wherein said sodium carbonate is precipitated as sodium carbonate monohydrate.
5. The method of claim 1 wherein water is removed

from said first aqueous solution while at least a portion of said potassium azide is precipitated.

6. The method of claim 1 wherein said second aqueous solution is formed at least in part by:

- (a) dissolving said sodium azide and said potassium carbonate in said water to form a third aqueous solution;
- (b) combining said third aqueous solution with said mother liquor; and
- (c) removing water.

7. The method of claim 1 wherein said separated sodium carbonate is washed to substantially remove entrained mother liquor.

8. The method of claim 7 wherein at least a portion of the wash liquor resulting from said washing is combined with said first mother liquor.

9. The method of claim 8 wherein sodium azide and potassium carbonate are combined with said wash liquor prior to combining said wash liquor with said first mother liquor.

10. The method of claim 8 wherein the concentration of azide ion present in said wash liquor is increased prior to combining said wash liquor with said first mother liquor.

11. The method of claim 10 wherein said concentration of azide ion in said wash liquor is accomplished by removing water from said wash liquor.

12. The method of claim 1 wherein said precipitated potassium azide is separated from said first mother liquor by centrifugation.

13. The method of claim 1 wherein said precipitated potassium azide is separated from said first mother liquor by filtration.

14. The method of claim 1 wherein said sodium carbonate is separated from said second mother liquor by centrifugation.

15. The method of claim 1 wherein said sodium carbonate is separated from said second mother liquor by filtration.

16. A cyclic process for producing potassium azide comprising:

- (a) at a first temperature, separating precipitated potassium azide from a first mother liquor obtained from step e;
- (b) adding heat and combining
  - (1) one equivalent of sodium azide per equivalent of said precipitated potassium azide separated from said first mother liquor,
  - (2) one equivalent of potassium carbonate per equivalent of said precipitated potassium azide separated from said first mother liquor,

- (3) water, and
- (4) said first mother liquor to form an aqueous solution at a second temperature which is higher than said first temperature;
- (c) removing water from said aqueous solution at said second temperature to precipitate one equivalent of sodium carbonate per equivalent of said precipitated potassium azide separated from said first mother liquor and to form a second mother liquor;
- (d) separating said precipitated sodium carbonate from said second mother liquor; and
- (e) cooling said separated second mother liquor to said first temperature to precipitate said potassium azide and to form said first mother liquor.

17. The method of claim 16 wherein said first temperature is about 25° C.

18. The method of claim 16 wherein said second temperature is about 80° C.

19. The method of claim 16 wherein said aqueous solution is formed at least in part by:

- (a) dissolving said sodium azide and said potassium carbonate in water to form an aqueous feed solution; and
- (b) combining said aqueous feed solution with said first mother liquor.

20. The method of claim 16 wherein said separated precipitated sodium carbonate is washed to substantially remove entrained mother liquor.

21. A cyclic process for producing potassium azide comprising:

- (a) at a first temperature, separating precipitated potassium azide from a first mother liquor obtained from step e;
- (b) adding heat and combining
  - (1) one equivalent of sodium azide perequivalent of said precipitated potassium azide separated from said first mother liquor;
  - (2) one equivalent of potassium carbonate per equivalent of said precipitated potassium azide separated from said first mother liquor;
  - (3) water; and

5
10

- (4) said first mother liquor to form an aqueous solution at a second temperature which is higher than said first temperature;
- (c) removing water from said aqueous solution at said second temperature to precipitate one equivalent of sodium carbonate per equivalent of said precipitated potassium azide separated from said first mother liquor and to form a second mother liquor;
- (d) separating said precipitated sodium carbonate from said second mother liquor; and
- (e) cooling said separated second mother liquor to said first temperature and removing water to precipitate said potassium azide and to form said first mother liquor.

22. The method of claim 21 wherein said first temperature is about 25° C.

23. The method of claim 21 wherein said second temperature is about 80° C.

24. The method of claim 21 wherein said aqueous solution is formed at least in part by:

- (a) dissolving said sodium azide and said potassium carbonate in water to form an aqueous feed solution; and
- (b) combining said aqueous feed solution with said first mother liquor.

25. The method of claim 21 wherein said separated precipitated sodium carbonate is washed to substantially remove entrained mother liquor.
